UNITED STATES PATENT OFFICE.

SAMUEL O. NAFZIGER, OF GOSHEN, INDIANA.

EXTENSION AND ROOF FOR SILOS.

1,186,675.

Specification of Letters Patent. Patented June 13, 1916.

Application filed September 25, 1915. Serial No. 52,600.

To all whom it may concern:

Be it known that I, SAMUEL O. NAFZIGER, a citizen of the United States, residing at Goshen, in the county of Elkhart and State 5 of Indiana, have invented certain new and useful Improvements in Extensions and Roofs for Silos, of which the following is a specification.

My invention relates to silos, particularly 10 to an extension roof for silos, and has for its object the provision of a device of this character which can be attached to any silo and which will extend vertically upward when employed as an extension forming a cylindrical casing; and when collapsed to form 15 a roof will form a conical water excluding covering; the component parts of the device being securely held together whether in the extended or collapsed position.

20 An important object is to provide means whereby the parts of the device will be effectually braced and supported at all times.

Another object is the provision of means 25 for simultaneously raising all parts of the roof to their vertically extended position.

With these and various other objects in view, such as means for guiding the sections together when descending to form a roof, together with the novel hinging means used, 30 in addition to the features of simplicity, durability, and efficiency, my invention consists in the novel construction and arrangement of parts, hereinafter described and illustrated in the accompanying drawings, 35 in which:

Figure 1 is a side view of my device extended, Fig. 2 shows the device collapsed to form a conical roof, Fig. 3 is a side view of the device with the front portion removed, Fig. 4 is a detail view of the cap shown in Fig. 2, and Figs. 5, 6, 7 and 8 are detail views.

Referring more particularly to the drawings, the numeral 1 designates a circular 45 supporting base for my device. A plurality of pieces of strap iron 2 are riveted or otherwise secured to the base 1 at equally spaced distances, the tops of said pieces extending above the base and having apertures 3 formed in the extended portion.

A plurality of roof sections 4 are hingedly mounted on said base by hook bolts 5, shown in Fig. 5. Each of the roof sections comprises one piece of material formed into triangular parts 6 and 7. The triangular part 55 6 has its narrowest portion at the top. The

side edges of this part 6 are bent at right angles forming portions 8 and 9, the portion 8 being three ply, to prevent its bending and the portion 9 forming an offset in 60 which the girder support 10 is secured. The triangular part 7 has its small end adjacent to the widest portion of part 6 or its bottom. The free end of the part 7 is curved slightly inward as at 11 to prevent it from striking 65 the girder 10 in the adjacent roof section.

The roof sections are kept from spreading at their lower ends by connecting braces 12 rigidly secured to the part 6 of one section and having a slot 13 in their free end. The 70 free ends of these braces are secured to the part 6 of the adjacent roof section by the hook bolts 5 which form the hinges for the roof sections 4. The hook bolts 5 pass through the apertures 3 in strap irons 2 and 75 are further passed through the angle irons forming the girders 10 and thence through the slots 13 in the braces 12 forming a flexible and secure hinge. The roof sections 4 are further braced by sliding braces 14 comprising a bar portion 15 and a receiving portion 16, as shown in Fig. 1. The bar 15 is secured to the part 6 of one roof section 4 and the receiving portion 16 is secured to 80 the part 6 of the adjacent roof section. 85

Guide members 17 are secured adjacent the top of the part 6 of the roof sections, as shown in Fig. 7. A bracket 18 is secured to one of the girders 10, and a tubular guide member 19 is secured to the 90 bracket. A conical cap 20 is secured to supports 21 on a tubular post 22 having an opening 23 in its lower end. The tubular post 22 is adapted to be inserted in the guide member 19. 95

Strap iron members 24, shown in Fig. 5, are secured to the lower ends of the girders 10 and have their free ends 25 bent V-shaped. Pulleys 26 are secured to the V-shaped portions 25 of the members 24. 100

A member 27 is hingedly secured at its upper end to the base 1 and has a set of pulleys 28 secured thereto near its lower end. A second pair of pulleys 29 are secured, one at each side of the member 27, directly to 105 the base 1.

A cable 30 is passed through all of the pulleys 26 and its ends are passed through the pulleys 28 and 29 and then secured together forming a loop 31. A cable 32 is secured in the opening 23 in the post 22 and then passed through pulleys 33 and 34 on 110

the bracket 18 and then it is passed under the roof at 35 and secured to the cable 30. A third cable 36 is secured to the loop 31 and passes down to the ground.

5 A cable hoop 38 is secured to the part 6 of the roof sections 4 to prevent the sections from spreading.

The operation of the device is as follows: The base 1 is set on the top of any ordinary silo wall and the roof sections 4 are secured to the base by the hook bolts 5 and the braces and guides are then assembled and the cables 30 and 32 are passed through their respective pulleys and the cable 36 is 15 then attached to the loop 31 in the cable 30. The device is then in its operative position and assembled. To raise the roof sections to act as an extension to the silo wall, all that is necessary is to pull on the cable 36 and this will first raise the cap 20 and leave the sections 4 of the roof free to rise and form the extension. Further pulling on the cable 36 will then raise the roof sections. After the roof sections are raised 25 the cable 36 is secured in any desired manner. To lower the sections it is only necessary to release the cable 36 when they will fall into the position shown in Fig. 2.

Having thus described my invention what 30 I claim is:

1. A combined extension and roof for silos comprising a base, a plurality of rectangular roof sections pivotally secured to said base, said sections being adapted to so 35 overlap each other that when collapsed they form a conical roof, a pulley secured to each of said roof sections below the pivot point, and a cable trained through said pulleys for simultaneously raising said sections.

40 2. A combined extension and roof for silos comprising a base, a plurality of rectangular roof sections hingedly secured to said base, a portion of each of said roof sections being raised in the form of a triangle, the inner edge of said portion forming an offset in which a supporting girder is secured, the outer edge of said portion being bent upon itself to form a three ply support, and all of said roof sections being 45 adapted to overlap and form a conical roof.

50 3. A combined extension and roof for silos comprising a base, a plurality of rectangular roof sections hingedly secured to said base, a portion of said sections being 55 raised in the form of a triangle, a girder

along the inner edge of said portion, extensions secured on said girders, said extensions being V-shaped, pulleys secured to said extensions, and a cable passed through said pulleys, whereby pulling on said cable 60 will raise all of said roof sections simultaneously to their extended positions.

4. A combined extension and roof for silos comprising a base, a plurality of roof sections hingedly secured to said base, girders secured to each of said roof sections, a bracket adjacent the top of one of said girders, a tubular guide member secured to said bracket, a post slidably mounted in said guide member, a conical cap secured to said 70 post, and means for raising said cap and said roof sections simultaneously.

5. A combined extension and roof for silos comprising a base, a plurality of roof sections hingedly secured to said base, girders secured to each of said roof sections, a bracket adjacent the top of one of said girders, a tubular guide member secured to said bracket, a post slidably mounted in said 75 guide member, a conical cap secured to said 80 post, and means for raising said cap and said roof sections simultaneously, said means comprising a plurality of V-shaped extensions secured to said girders, pulleys secured to said extensions, other pulleys secured to said base, a cable passed through all of said pulleys, and a plurality of pulleys secured to said bracket, a cable secured to the lower end of said post and passed through said last named pulleys and secured 90 to said first named cable.

6. A combined extension and roof for silos comprising a base, a plurality of roof sections hingedly secured to said base, parts of said roof sections being raised in the form 95 of a triangle, means for simultaneously raising said roof sections, and means for preventing said roof sections from spreading when in their extended position, said means comprising sliding braces adjacent the bottoms of said roof sections and a flexible hoop secured to said raised portion of each roof section.

In testimony whereof I hereto affix my signature in the presence of two witnesses. 105

SAMUEL O. NAFZIGER.
